UNITED STATES PATENT OFFICE.

NEHEMIAH GUTHRIE, OF ITALY, TEXAS, ASSIGNOR OF ONE-HALF TO
JOHN L. ANDERSON, OF ITALY, TEXAS.

HAME-TUG.

SPECIFICATION forming part of Letters Patent No. 794,977, dated July 18, 1905.

Application filed April 12, 1905. Serial No. 255,131.

To all whom it may concern:

Be it known that I, NEHEMIAH GUTHRIE, a citizen of the United States, residing at Italy, in the county of Ellis and State of Texas, have 5 invented new and useful Improvements in Hame-Tugs, of which the following is a specification.

My invention pertains to hame-tugs; and it consists in a tug embodying the peculiar and 10 advantageous construction hereinafter described, and particularly defined in the claim appended.

In the accompanying drawings, forming 15 part of this invention, Figure 1 is a perspective view illustrating the hame-tug constituting the preferred embodiment of my invention as connected to a trace. Fig. 2 is a longitudinal section of the tug with some parts in elevation and the trace omitted. Fig. 3 is 20 a transverse section taken in the plane indicated by the line 3 3 of Fig. 2, and Fig. 4 is a detail longitudinal section taken in the plane indicated by the line 4 4 of Fig. 3.

Similar letters designate corresponding 25 parts in all of the views of the drawings, referring to which—

A is a trace, of leather or other suitable material, and B is my novel tug as a whole.

As clearly shown in the drawings, the tug 30 B comprises a draft-bar *a*, of oblong form in cross-section having a head *b* at its forward end and means, preferably a leather lug *c* and a buckle *d*, at its rear end for connecting it to trace A, a casing *e*, provided 35 with a loggerhead *f* or other means to connect it to a hame, (not shown,) and also provided with an interior abutment *g*, loosely receiving the rod *a*, and a coiled spring *h*, having coils of oblong form, Fig. 3, surrounding the bar *a* and interposed between the head *b* thereof and the abutment *g*, so as to cushion 40 rearward draft on the bar, as when a horse commences to pull, and thereby relieve the strain on a horse and effectually prevent breakage of the harness. The casing *e* is made up 45 of a substantially flat inner section *k*, of sheet metal, and a concavo-convex outer section *l*, of sheet metal, the edges of which are riveted at intervals to those of the section *k*, as indicated by *m*. These sections *k* and *l* are pro-

vided with grooves *m'*, Fig. 4, which receive the edges of and hold the abutment *g*, and their forward portions are disposed at opposite sides of and riveted to the loggerhead *f*, as shown. The outer section *l* is also provided with keeper-loops *p*, of sheet metal, designed to receive and hold the surplus portion of the trace A after the manner illustrated in Fig. 1.

The casing-sections *k* and *l*, the loops *p*, 60 the rod *a*, the abutment *g*, and the spring *h* are all preferably of steel with a view of enabling them to withstand the rough usage to which hame-tugs are ordinarily subjected, and thereby prolong the usefulness of the improved tug as a whole.

It will be gathered from the foregoing that the draft-bar *a*, the spring *h*, and the casing *e* are of flat and narrow form, and hence present about the same thickness as an ordinary 70 hame-tug, as is desirable; but it will be noticed that notwithstanding such flat and narrow form the spring is highly efficient in cushioning the draft-bar *a*, while the casing *e* is adapted to effectually protect the said 75 spring against injury and the weather. It will also be noticed that the abutment *g* is securely clamped and held between the sections *k* and *l* of the casing *e*, and hence is not likely to be casually moved lengthwise of 80 the casing by pull imposed on the bar *a* and spring *h*.

I have specifically described the construction and relative arrangement of the parts in the present embodiment of my invention in 85 order to impart a definite understanding of the said embodiment. I do not desire, however, to be understood as confining myself to the specific construction and arrangement of parts, as such changes or modifications may 90 be made in practice as fairly fall within the scope of my invention as claimed.

Having described my invention, what I claim, and desire to secure by Letters Patent, 95 is—

In a hame-tug, the combination of a flat-form casing comprising an inner, sheet-metal section and an outer, sheet-metal section; said sections having their edge portions riveted together and also having grooves at an inter- 100

mediate point in the length of the casing, means at one end of the casing for connecting the same to a hame, an apertured abutment arranged in the grooves of and clamped between the casing-sections, a draft-bar, of oblong form in cross-section, extending loosely through the abutment and having a forward head, and a coiled spring surrounding the draft-bar, within the casing, and interposed be-

tween the head of the bar and the abutment; to the said spring having oblong coils.

In testimony whereof I have hereunto set my hand in presence of two subscribing witnesses.

NEHEMIAH GUTHRIE.
